UNITED STATES PATENT OFFICE

155,247

DESIGN FOR A FINGERLESS GLOVE

Margaret Wiesenthal, New York, N. Y., assignor to Gloria Gloves, Inc., New York, N. Y., a corporation of New York

Application April 20, 1948, Serial No. 145,823

Term of patent 3½ years

(Cl. D3—11)

To all whom it may concern:

Be it known that I, Margaret Wiesenthal, a citizen of the United States of America and residing at New York, county and State of New York, have invented a new, original, and ornamental Design for a Fingerless Glove, of which the following is for a specification, reference being made to the accompanying drawing, forming part thereof.

Fig. 1 is a rear view of a fingerless glove showing my new design as it appears in wearing position, the outline of the wearer's hand being shown in dotted lines for convenience of illustration.

Fig. 2 is a front view thereof, and

Fig. 3 is a top plan view of the glove as it appears with the cuff in open position.

I claim:

The ornamental design for a fingerless glove, substantially as shown and described.

MARGARET WIESENTHAL.
